PIVOTED HOIST WITH ADJUSTABLY SUPPORTED ARM

Joseph Hauk, Waukesha, Wis., assignor to Allis-Chalmers Manufacturing Company, Milwaukee, Wis., a corporation of Delaware

Application May 25, 1948, Serial No. 29,145

6 Claims. (Cl. 212—17)

1

This invention relates in general to a hoisting device and more particularly to a hoist which may be adapted for operating a device for filing the slots of a cylindrical laminated core.

In the use of other known hoist devices, there exists a difficulty in adjusting the hoist for quickly aligning its cable with a slot of the core and in readjusting the hoist for quickly aligning the cable with another slot of the core.

To reduce the time necessary for adjusting a device of the type considered, it is advantageous to use a hoist which may be mounted on the end of a core and which provides means for adjusting the radial position and the angular position of the cable support.

It is therefore an object of the invention to provide suitable power means such as a hoist for operating a device for filing the slots of a cylindrical laminated core.

Another object is to provide a pivoted hoist which is supported at a point adjacent the cable pulley and at another point.

Another object is to provide a pivoted hoist in which the cable pulley and a support may be adjusted radially independently of each other.

Another object is to provide a pivoted hoist which may be adjusted radially for supporting the hoist on the frames of cores of different diameters.

Other objects and advantages will be apparent from a consideration of the following description taken in consideration with the accompanying drawing, in which:

Fig. 1 is a view in elevation of a pivoted hoist built in accordance with the present invention and shown mounted on an end of a cylindrical laminated core, each having parts thereof broken away;

Fig. 2 is a top view of the hoist shown in Fig. 1, with additional parts thereof broken away; and

Fig. 3 is a stepped, cross sectional view of the hoist shown in Fig. 1, taken along the line III—III.

Referring more particularly to the drawing by characters of reference, numeral 4 generally designates a cylindrical laminated core, such as the core of a dynamoelectric machine. The core is assembled in a stator frame 5 on which the hoist may be mounted through uprights 6 bolted or clamped firmly to the frame.

Horizontal beams 7 of the hoist span the core along opposite radii and are fastened to the uprights 6 by suitable means such as bolts 8 which may be loosened for centering the hoist on the core.

2

An annular pivot plate 9 having longitudinal ribs 10 is rigidly mounted on the beams 7 by bolts 11 fastening the ribs to the beams. The inner part of pivot plate 9 forms a hub 12 containing a bushing 13 for a shaft 14.

The shaft 14 is keyed at its upper end to a worm wheel 15 having a hub 16. The worm wheel is held in place on the shaft by a pair of shaft collars 17 fixed to the shaft by pins 18 on each side of the hub 16. The lower shaft collar 17 is seated on the bushing 13 and the hub 12 of plate 9 for supporting the shaft 14.

The worm wheel 15 is operatively connected to a worm 19 fixed to a shaft 20 which is supported in bearings 21 mounted on beams 7. Fastened at each end of shaft 20 for rotating the worm 19 is a handwheel 22.

A table 24 is welded to the lower portion of shaft 14. The bottom surface 25 of pivot plate 9 contacts part of the upper surface 26 of the table. The table extends beyond pivot plate 9 in a generally diametrical direction. Its lower portion is machined to form ribs 27 to which are attached rails 28. The ribs 27, the rails 28, and the undersurface of table 24 define a slide bed. A slide member 30 having machined grooves 31 is inserted in the bed with the rails 28 fitting into the grooves 31 for slidably supporting the slide member. The slide and the table cooperate to define a channel 32. Contained in channel 32 and rigidly attached to the slide 30 is a nut 33. A screw 34 extending longitudinally of the table in channel 32 is fitted in nut 33. The screw is pivotally supported in the ends of the table, and is secured against longitudinal movement in the table by collars 35 and pins 36 fastened to the ends of the screw 34 at each end of the table.

At one end of the table a handwheel 38 is mounted for turning a set of gears 39. One of the gears 39 is fixed to an end of the screw 34 for turning the screw.

The slide is provided for adjusting the radial position of at least the guiding pulley of the winch used for drawing a filing device through the slots of core 4. In the embodiment shown in Fig. 1, to the slide 30 are attached, as by welding, a pair of plates 40 forming an essential part of the framework of a winch 41 of any known construction. The winch may comprise a threaded drum 42, a cable 43 connected thereto, and a motor 44 of any suitable known type for rotating the drum 42. The winch may be provided with any suitable known control mechanism such as a clutch 45, for operatively connecting the motor to the drum, and with a brake 46 for retarding movement of the drum. The motor 44 is shown

as an air operated motor driven by compressed air supplied from a suitable source (not shown) through a hose 47.

Pivottally supported in the frame formed by the plates 40 is a pulley 49 on which the cable 43 may be guided. The winch frame supports an arm 50 comprising a pair of channel irons 51 each slidably mounted between a pair of L-shaped rails 52 welded to the plates 40. The outer ends of the channel irons are connected together by a cross member 54 for retaining each channel iron between its pair of L-shaped rails.

For adjusting the radial position of arm 50, channel irons 51 are connected to the plates 40 by a pair of screws 56. Each screw may be locked by a pair of lock nuts 57 to a flange 58 welded to the plates. A pair of lugs 59, rigidly attached to channel irons 51, are tapped and threaded for receiving screws 56. Nuts 60 may lock the screws 56 to the lugs 59.

For additionally supporting the winch 41, an adjustable leg 62 comprising a screw 63 is connected to the arm 50 through cross member 54. The screw of leg 62 may have a pivot foot 64, which is shown resting on an end surface of the frame 5. The leg 62 may also be provided with a handwheel 65 for turning the screw 63.

The preferred embodiment of the hoist herein described is shown mounted on a frame 5 of a stator of a dynamoelectric machine, and the cable 43 is shown connected to a filing device 66 shown positioned in one of the slots 67 disposed about the bore of the cylindrical laminated core 4. In the following description it will be assumed that the axis of core 4 is vertical, but it will be understood that the hoist may also be used in connection with a core having a horizontal or inclined axis.

To use the hoist for operating the filing device as shown, the uprights 6 are mounted on frame 5 on opposite radii. Beams 7 are rested on uprights 6 in proper position bringing the axis of shaft 14 in coincidence with the axis of core 4. The beams then are fastened to the uprights by means of bolts 8. The bolts allow a predetermined range of adjustment of the distance between uprights 6 to permit mounting the hoist on frames of different diameters.

After beams 7 are thus positioned, the hoist is adjusted to bring cable 43 in one of the slots of the core. Handwheel 38 is rotated, causing screw 34 to turn in nut 33. The nut 33, unable to turn with the screw, travels along the screw and moves the slide 30 in the bed of table 24. Since the slide is welded to plates 43, turning handwheel 38 causes winch 41, including pulley 49, and the arm 50 with its leg 62, to be moved radially with respect to the table 24 and to the core. Handwheel 38 is rotated until cable 43 is aligned with one of the slots 67 of the core, as shown in Fig. 1.

The leg 62 is then positioned above a surface of the frame 5 by adjusting the radial position of arm 50 independently of the radial position of winch 41. For this purpose, nuts 51 are loosened, the arm is moved radially until the leg 62 is positioned properly above the core, and the arm is locked in its position by tightening nuts 51 against flange 58. The effective length of the leg 62 then is adjusted by turning the screw 63 until there is a small clearance between the surface of frame 5 on which the leg is to stand and the foot 64 of the leg.

The hoist then is properly positioned for use with the filing device 66 for filing the slots of the

cylindrical laminated core 4. Before the filing operation is begun, handwheel 38 is rotated to move the winch and the leg radially inward until the alignment of cable 43 is brought within the bore of the core. The filing device 66 may be attached to the cable, and the winch 41 operated to lower the filing device below the core 4.

Handwheel 38 then is oppositely rotated to move the winch 41 and leg 62 radially outward for realigning the cable 43 with the slot 67. The filing device being properly inserted in the slot, the winch is operated, winding the cable 43 over pulley 49 and on the drum 42 and drawing the device upward through the slot. This operation may be repeated if it is desired to again draw the filing device through the same slot.

When the filing device is being drawn through a slot, the reaction of the core 4 to the filing device, transmitted through the cable 43, pulls down on the winch and causes the foot 64 of leg 62 to be pressed firmly against the frame 5. The clearance between the leg and the frame is taken up by the resiliency of the beams 7 and of the arm 50. The leg 62 thus additionally supports the table 24. When the filing device is drawn clear of the slot, the resiliency of the structure causes the foot 64 to lift and again have clearance from the surface of the frame 5. Therefore the radial position of the winch 41, its pulley 49, and the leg 62, may be adjusted without readjusting the length of the leg 62.

For filing another slot of the core 4, such as an adjacent slot, the winch and leg are moved radially inward. Handwheel 22 then is rotated, revolving worm 19 and worm wheel 15. Shaft 14 being rigidly connected to worm wheel 15 and to table 24, rotates with the worm wheel and pivots table 24 with it. The angular position of table 24 is so adjusted that the cable 43 is radially aligned with the slot to be filed. The hoist then may be adjusted as described above preparatory to lowering the device out of the slot, and for realigning the cable with the device when it is inserted in the slot.

Although but one embodiment of the present invention has been illustrated and described, it will be understood that changes and modifications may be made therein without departing from the spirit of the invention or the scope of the appended claims.

It is claimed and desired to secure by Letters Patent:

1. A hoist comprising a fixed horizontal beam, a vertically pivoted table supported on said beam, a power winch attached to said table, a leg connected to said winch for additionally supporting said winch, and means for adjusting the radial positions of said winch and said leg.

2. A hoist comprising a fixed horizontal beam, 60 a vertically pivoted table supported on said beam, a power winch attached to said table, a leg connected to said winch, common means for adjusting the radial positions of said winch and said leg, and additional means for adjusting the radial position of said leg independently of the position of said winch.

3. A hoist for operation above a fixed structure, said hoist comprising a horizontal beam, means for supporting said beam at a fixed height above 70 said structure, a vertically pivoted table supported on said beam, a winch mounted on said table at a fixed height above said structure, a leg extending downward from said winch for additionally supporting said winch on said structure, and means for adjusting the length of said

leg to conform to the height of said structure.

4. A hoist comprising a fixed horizontal beam, a vertically pivoted table supported on said beam, a power winch attached to said table, a leg connected to said winch for additionally supporting said winch, means for adjusting the length of said leg, and means for adjusting the radial positions of said winch and said leg.

5. A hoist comprising a fixed horizontal beam, a vertically pivoted table supported on said beam, a power winch attached to said table, a leg connected to said winch, means for adjusting the length of said leg, common means for adjusting the radial positions of said winch and said leg, and additional means for adjusting the radial position of said leg independently of the position of said winch.

6. A hoist comprising a fixed horizontal beam, a vertically pivoted table supported on said beam, a power winch attached to said table, a leg connected to said winch for additionally supporting

said winch, and means for adjusting the radial position of said leg to cause said leg to effect its supporting action at an adjustable distance from the pivotal axis of said table.
